John Martino & James Horton of Philadelphia, Pa
Letters Patent No. 1331. Dated April 10, 1860

The schedule referred to in these Letters Patent and making part of the same.

To all whom it may concern:

Be it known that we, John Martino and James Horton of Philadelphia, Pennsylvania, have invented or produced a new and original design for plates of a cooking range, and we do hereby declare the following to be a full, clear and exact description of the same, reference being had to the accompanying drawing which forms a part of this specification, and in which

Fig. 1. represents the front plate of the range, and
Fig. 2. one of the end plates.

The front plate, Fig. 1. is edged at the top and sides with a plain moulding within which are two rows of denticulated moulding b. and d. both of the latter extending along the bottom of the plate. The front plate has two oven doors B.B. each door being edged on three sides with a plain rounded moulding c. and each door having a foliated ornament of such a form that when the doors are closed the two ornaments represent one mass of foliage.

2

Dec 1231

Near one side of the plate is another door C. the upper portion of which is edged with a plain rounded moulding enclosing a foliated ornament of a character similar to that on the doors B. B.

The lower portion of the door has four openings edged with plain beads, and the lower edge of this door has denticulated mouldings similar to those on the other parts of the stove.

Above the door C. a portion of the plate marked D. is raised for receiving the swing door E. a wreath of foliated ornaments being cast on this raised portion on each side and below the lower edge of the door, which has a plain moulding enclosing an oval shield and four ornamental sprigs -

The end plate represented by Fig: 2. is furnished on the edges with denticulated mouldings forming a panel which contains a foliated ornament both the latter and the mouldings being of a character similar to those on the front plate.

We claim the ornamental figures and forms represented in and by the accompanying drawing the whole forming the front and end plates of a cooking range.

In testimony whereof we have signed our names to this Specification in the presence of two subscribing witnesses.
